Primary Examiner — Sheryl Lane*Assistant Examiner* — Aula Soroush(74) *Attorney, Agent, or Firm* — Foley & Lardner LLP; Sunit Talapatra(57) **CLAIM**

I claim the ornamental design for a fire hydrant pet treat, as shown and described.

DESCRIPTION

FIG. 1 is a perspective view of a fire hydrant pet treat showing my new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The dot-dash lines in the drawings illustrate the bounds of the claim which form no part of the claimed design.
